Application February 16, 1932, Serial No. 593,280

31 Claims. (Cl. 68—248)

This invention relates to improvements in clothes wringers and particularly to the power-operated type such as may be applied to electrically driven washing machines.

5 An important object of the invention has been to produce a wringer which is safe in its operation, being substantially free from any danger of drawing the fingers of the operator between its rolls. At the same time the construction 10 contemplated may be power-operated not only for the purpose of driving the rolls in a wringing operation but also for the purpose of bringing the rollers together under pressure and for releasing them from such pressure.

15 A further object of the invention has been to produce a wringer unit which is low in construction and presents a more pleasing appearance, in conjunction with a washing machine, than wringers heretofore employed. In the accomplishment of these and other objects, the improved wringer is adapted to operate effectively and efficiently and may be of relatively inexpensive construction.

20 A feature of the new wringer is the mounting 25 of the presser rollers with their axes in substantially the same horizontal plane with provisions for feeding the clothes into the bight of the rollers from either side. The rotation of the rollers is preferably arranged to be always in the same 30 direction, which is such that the clothes will be discharged from the upper side. The lower portion of the wringer is so enclosed and guarded that no access is provided for anything solid of unusual thickness. This makes it impossible to 35 have the hand caught between the rollers since the latter tend to force the hand away at the top and the hand cannot reach in to the bight of the rollers from below. Positioning of the pair of rollers with their axes in substantially the same 40 horizontal plane has made it more difficult to introduce the clothes between the rollers but this difficulty has been overcome by the provision of special feeding devices. Novel means have also been provided for bringing the rollers 45 together under a variable pressure.

50 Other objects and features of the invention will appear from a detailed description of several illustrative forms of the same which will now be given in conjunction with the accompanying drawings, in which:

Fig. 1 is a top plan view of a wringer embodying features of the present invention, a cover plate being removed to show certain of the operating mechanism;

55 Fig. 2 is a view partly in side elevation and

partly in vertical section along the line 2—2 of Figure 1;

Fig. 3 is an end view of the wringer with a portion of the casing broken away to disclose the mechanism;

Fig. 4 is a vertical, sectional view taken along the line 4—4 of Figure 1;

Fig. 5 is a detail view in section along the line 5—5 of Figure 4;

Fig. 6 is a vertical, sectional view along the line 6—6 of Figure 1, but with the rollers separated;

Fig. 7 is a detail view in section along the line 7—7 of Figure 2;

Fig. 8 is a detail view in horizontal section along the line 8—8 of Figure 7;

Figs. 9 and 10 are detail, sectional views along the lines 9—9 and 10—10, respectively, showing the roller tensioning devices;

Fig. 11 is a detail view in vertical section along the line 11—11 of Figure 1;

Fig. 12 is a detail view of a portion of the mechanism for bringing the rollers together under pressure;

Fig. 13 is a detail view in vertical section, along the line 13—13 of Figure 14, of certain clothes feeding devices that may be employed;

Fig. 14 is a detail view in plan of one end of the rollers, showing the feeding devices below;

Fig. 15 is a view similar to Figure 13, along the line 15—15 of Figure 16, showing a modified clothes feeding mechanism;

Fig. 16 is a plan view of one end of the construction shown in Figure 15;

Fig. 17 is a detail view in vertical section showing a further modification of the clothes feeding mechanism;

Fig. 18 is a detail, sectional view along the line 18—18 of Figure 17;

Fig. 19 is a longitudinal, vertical section through a modified form of wringer;

Fig. 20 is a transverse, vertical section along the irregular line 20—20 of Figure 19;

Fig. 21 is a detail view in plan of the driving mechanism for the rolls of the modified construction;

Fig. 22 is a detail view in vertical section along the line 22—22 of Figure 19 showing the roller tension controlling devices of the modified wringer construction;

Fig. 23 is a detail view in side elevation of the roller control clutches, with the parts in idle position;

Fig. 24 is a sectional view along the line 24—24 of Figure 23, and

Fig. 25 is a transverse, sectional view through the modified wringer, along the lines 25-25 of Figure 19, showing the tiltable drain.

Referring now to Figures 1 to 12 of the drawings, a wringer embodying the features of the present invention is shown as provided with a frame and enclosing casing 10 having secured thereto, or integral therewith, a gear housing 11 terminating at its lower end in suitable means 10 for attaching the wringer to a washing machine in any appropriate, conventional way. Housing 11 is provided with flange 12. A shaft 13 extending into the gear housing is adapted to be connected in a well known manner with a vertically disposed shaft at the side of a power driven washing machine for the purpose of driving the moving parts of the wringer. At the upper end of the shaft 13 there may be provided a bevel pinion 14 meshing with a bevel gear 15 secured to a shaft 16. This shaft, adjacent its opposite end, carries a clutch member 17 which is keyed or splined to the shaft so as to rotate therewith and at the same time is shiftable longitudinally thereof. Projections 18 at the end of the clutch member 17 are adapted to enter a recess 19 in a pinion 20 secured to a shaft 21. This shaft extends substantially the full length of the wringer and serves to support a roller 22, preferably formed of rubber, or similar material, and serving 30 as one of a pair of wringer rolls. The companion roller 23 is carried by a shaft 24 which likewise extends substantially the full length of the wringer and is supported with its axis in substantially the same horizontal plane as the axis 35 of the shaft 21. A pinion 25 secured to the shaft 24 is adapted to mesh with the pinion 20 and thus causes the two rollers to rotate in unison.

For the purpose of shifting the clutch member 17 to couple the pinion 20 to the shaft 16, or to 40 disconnect these parts as desired, there is provided an element 26 pivoted at 27 on a suitable portion of the frame. This element is forked in rear of the pivot 27, as viewed in Figure 1, and carries a pin or roller 28 on each branch of the 45 fork adapted to engage in a groove 29 formed around the periphery of the member 17. A spring 30 coiled around the pivot pin 27 normally tends to rock the element 26 in a clockwise direction (Fig. 1) to engage the clutch by carrying the 50 projections 18 into the groove 19 of the pinion 20. At its free end the element 26 is provided with a curved contact portion 31 adapted to engage the face of a cam lug 32 carried by a pitman member 33. This member, as will more clearly appear 55 hereinafter, is given primarily a sliding movement but at the same time partakes of a slight pivotal movement. It is pivotally connected at one end to a lever 34 which in turn is pivotally supported at its upper end by a pivot pin 35. At 60 its opposite end the member 33 is enlarged to provide an eccentric strap 36 adapted to surround an eccentric 37 carried by or formed integral with a drum 38 freely supported by the shaft 16.

65 Suitable means are provided for temporarily connecting the drum 38 with the shaft 16 at will for imparting a partial rotation to the drum. It will be apparent that upon each revolution of the drum 38 the member 33 will be reciprocated 70 due to the action of the eccentric 37. The driving connection between the drum 38 and the shaft 16 is such that these parts may be coupled under manual control for a half revolution and will then be automatically disconnected until the clutch is 75 again made effective by a further manual opera-

tion. For this purpose the drum 38 is provided with a recess 39 in one face adapted to receive a driving element 40 which is keyed or splined to the shaft 16. This driving element is formed with a series of recesses 41 having square shoulders adapted to cooperate with the end 42 of a dog 43 pivotally mounted at 44 upon the drum 38. A spring pressed plunger 45 is adapted to rock the dog 43 clockwise (Fig. 7) to engage the end 42 in one of the notches 41. Rocking of the dog is prevented, however, by the engagement of a projection 46 with the outer surface of the dog. In the operation of the wringer the shaft 16 and element 40 will be constantly driven and when it is desired to produce a rotation of the rolls 22 15 and 23, through the connections previously mentioned, the drum 38 is coupled to the element 40 for a half revolution so as to cause the element 33 to be shifted from the position shown in Fig. 6 to the position shown in Figure 3. This will 20 serve to carry the camming lug 32 into the position shown in Fig. 1 in which the spring 30 will shift the clutching element 17 to couple the pinion 20 with the shaft 16. As will be presently explained, the shifting of the projection 46 to permit 25 rocking of the dog 43, and thus bringing about a half revolution of the drum 38, is under manual control. For this purpose the projection 46 is carried by a rocking member 47 pivotally supported at 471 by a portion of the frame. The 30 member 47 is in the form of a bell crank, one arm of which is engaged by a spring 48 to normally urge the projection 46 into the path of the dog 43. A plunger 49, however, carrying a knob or button 50 at its upper end is adapted to be depressed against the action of a spring 51 and serves to rock the member 47 to carry the projection 46 out of the path of the dog 43, in the manner explained.

Should it happen that at the time the projection 46 is moved out of the path of the dog 43 the end 42 is adjacent a high point of the clutch element 40, so that the plunger 45 is unable to rock the dog and should the button 50 be released instantaneously, the projection 46 would return to 45 its normal position and possibly prevent rocking of the dog, thus preventing its engagement with the element 40, if no additional means were provided. However, to avoid this possibility, a separate element 52 is pivotally supported on the pin 50 44 adjacent the dog 43. This element is provided with a tail 53 normally adapted to engage the under surface of the projection 46. However, when the latter is withdrawn upon depression of the button 50, the element 52 is rocked by a spring 54, mounted within a socket in the dog, which 55 engages a pin 55 secured to the element and is permitted a limited movement by a slot in the dog 43. Thus, even though the dog 43 is prevented from rocking at the moment of depression 60 of the button 50, the element 52 may be rocked to carry its tail 53 across the face of the projection 46 and thus prevent the return of the latter into the path of the dog even though the button is immediately released. By having the spring plunger 65 cooperate with a portion of the element 52, as shown, in lieu of directly engaging the dog, the spring 54 may be eliminated if desired.

When the end 42 of the dog is engaged in the manner explained, the drum 38 will be rotated 70 with the shaft 16 until the dog 43 engages a projection 56 similar to the projection 46 carried by an opposite branch of the same member 47. It will be understood that in the interim the button 50 will have been released and the mem- 75

ber 47 will then be rocked by the spring 48 to carry the projection 56 into the path of the dog. Cooperation of the projection with the outer surface of the dog will serve to rock the latter about its pivot 44 and will carry it out of engagement with the notch 41 so as to uncouple the drum 38. The half revolution of the drum prior to such uncoupling will produce the shifting of the member 33 and lever 34 from the position of Fig. 6 to that of Fig. 3.

Should it now be desired to disconnect the rolls from the driving power, it is simply necessary to again depress the button or knob 50. This will again serve to rock the member 47 and will withdraw the projection 56 from cooperation with the dog 43 and element 52. The dog will then connect the drum 38 with the rotating element 40 and will carry the eccentric through a half revolution until the dog and the element 52 are again engaged by the projection 46 to uncouple the drum from the shaft 16. This operation of the drum will shift the pitman member 33 to the right (Fig. 6), thereby releasing the pressure between the rollers and causing the cam lug 32 to uncouple the pinion 20 from the shaft 16.

The roller 22 is preferably supported at its opposite ends by ball or roller bearing units 57 and 58. These may be more or less fixedly mounted in the frame in any suitable way. In order to enable the ready assembly and repair of the parts, some suitable form of readily detachable connection is most conveniently provided between the bearing units and the frame. The relation is preferably such, however, that when the bearing units are applied, they are held stationary on the frame. The roller 23 may similarly be supported at its opposite ends by ball or roller bearing units 59 and 60. These units, however, are not fixedly mounted on the frame but are adapted to move relatively to the frame to permit a yielding pressure to be established and released between the rollers. For this purpose the unit 59 is carried by a slide 61 which may be suitably guided and supported by plates or guideways 62 and 63 attached to a portion of the frame. Similarly the bearing unit 60 is carried by a slide 64 retained and guided between elements 65 and 66 secured to the frame. The arrangement and mounting of the slides or blocks 61 and 64 is such that the shaft 24 and roller 23 may be shifted in a horizontal plane toward and away from the roller 22. Slide 64 has pivotally connected at 67 a lever 68 which is pivotally mounted upon the frame at 69. This lever corresponds with the lever 34 to which the plate 61 is pivotally connected at 35, but its pivot is fixed in lieu of being shiftable, as is the intermediate pivot of lever 34. A spring 70 extended between a stud on the frame and the lower arm of the lever 68 tends to rock the latter in a clockwise direction (Fig. 4) so that the roller 23 will be drawn away from the roller 22.

For the purpose of yieldingly shifting the slides 61 and 64 to carry the roller 23 against the roller 22, a spring bar 71 is connected between downwardly extending portions 72 and 73 of the levers 34 and 68, respectively. The spring bar 71 (as best shown in Figs. 9 and 10) carries a pivot lug 74 provided with inclined surfaces adapted to cooperate with correspondingly inclined surfaces on a pair of blocks 75 and 76. These blocks are carried by a screw 77 which is adapted to be turned through a universal

connection with a shaft 78 provided at its outer end with a handle 79. This handle may suitably extend to a point beyond the frame of the wringer so that it may be turned to adjust the relative positions of the blocks 75 and 76. The bar 71 and the cooperating parts are conveniently supported and retained in position by a portion of the frame beneath the rollers. It will be apparent that as the blocks are drawn more closely together, the pivot lug 74 will be held further out along the inclined faces of the blocks and a more direct and rigid connection will be provided between the levers 34 and 68. Now it will be apparent that as the lever 34 is drawn toward the left in Fig. 6 by the pitman 33, the end 72 will press against the end of the spring bar 71 and will cause the opposite end of the spring bar to produce a substantially equal force in the opposite direction upon the end 73 of lever 68. Since the pitman 33 is connected to the lever 34 at substantially the midpoint of the latter, the lever will first pivot about its point of contact with the bar 71 while the upper end of the lever will shift the slide 61 to carry the corresponding end of the roller 23 against the roller 22. The lower end of lever 34 will then press more forcibly against the bar 71, i. e. with a force equal to that applied to the slide 61, and will transmit this to the lower end of lever 68, thereby causing the slide 64 and the corresponding end of roller 23 to be shifted toward roller 22. As the movement of the pitman 33 continues, the pressure applied at the two ends of the roller 23 by the slides 61 and 64 will be substantially equalized by the inter-connections pointed out. It will also be apparent that as the blocks 75 and 76 are drawn together by operation of the handle 79, the tension applied to the rollers may be increased or by an opposite adjustment the tension may be decreased.

From the foregoing it will be clear that operation of the knob 50 will not only control the driving connection between the rollers and the shaft 16 but will also control the application and removal of pressure between the rollers. The arrangement is such that as the clutch 17 is shifted to effect a driving connection between the shaft 16 and the rollers, tension will simultaneously be set up between the rollers. Similarly, upon a subsequent operation of the knob 50 to disconnect the rollers from the driving mechanism, the tension between the rollers will be released. The direction of rotation of the rollers will always be the same and will be such as to carry the clothes upwardly between the rollers, i. e., as viewed in Fig. 4 roller 22 will be rotated counter-clockwise and roller 23 clockwise.

Beneath the rollers there is flexibly mounted a clothes guide and supporting member 80, preferably formed of sheet metal. This guide member may be suitably supported at its four corners by studs 81 carried by plates 82 slidably mounted upon adjacent portions of the main frame. The plates 82 may be drawn upwardly by springs 83 attached at their upper ends to ears 84 formed on a portion of the frame. The studs 81 may suitably be provided with grooves cooperating with bayonet slots formed in the main frame. This will enable the plates 82 to be readily mounted upon and detached from the main frame. The clothes guide 80 may conveniently be formed with hooked extensions at the four corners to engage the studs 81 in the manner best shown in Figure 4. This, it will be

apparent, will form a resilient support and will tend to yieldingly draw the clothes guide into engagement with the under surface of the rollers. As clothes are fed between the guide 80 and either of the rollers, the guide will simply be depressed on one side, tensioning the springs 83 and permitting the free passage of the clothes. The shape of the guide is such that it will serve to lead the clothes into the bight of the rollers. 5 Any water which is wrung from the clothes will be collected in the concave portions of the guide member 80 and will be discharged through openings 85 in these portions to a suitable drain 86 secured between the side members of the main 10 frame. If desired a tiltable deflector might be provided in a well known manner to direct the water from the openings 85 to one side or the other of the drain 86. As the clothes pass between the rollers and emerge from the top, they 15 may be directed over either of a pair of guides 87 pivotally supported by rods 88. These rods preferably extend from one end of the frame to the other and serve as convenient tie rods while at the same time they permit the clothes guides 20 87 to be pivotally supported in the manner shown. The guides 87 may be swung upwardly about their pivots whenever it is desired to have 25 access to the rollers.

A typical operation of the wringer just described may be briefly outlined as follows: Let it be assumed that the shaft 16 is being driven by the power means of a washing machine but the clutch member 17 is ineffective. The eccentric 37 will then be in the position shown in Figure 30 6 and the pressure between the rollers will be released. Should it be desired to put the wringer into operation the knob 50 is simply depressed. This will cause the projection 46 to be withdrawn from engagement with the dog 43 and 35 40 will serve to connect the drum 38 with the shaft 16. The drum will be rotated through a half revolution and will then be uncoupled from the shaft 16 by engagement of the dog 43 with the projection 56. During this half revolution of 45 the eccentric 37 it will draw the pitman 33 toward the left (Figure 6) and thus force the roller 23 yieldingly against the roller 22. At the same time the cam lug 32 will be withdrawn from the portion 31 of the element 26 and the spring 30 50 55 will shift the member 17 to couple the pinion 20 to shaft 16. Rotation of the rollers under tension will continue until the knob 50 is again depressed. This will again release the drum 38 for a half revolution during which the eccentric 37 will shift the pitman 33 back to the right. Lug 32 will act to uncouple pinion 20 from shaft 16 at the same time that the tension between the rollers is released.

A modified construction of the clothes guide beneath the rollers is illustrated in Figs. 13 and 14. As here shown the guide may suitably comprise a sheet 90 of metal, or other flexible material, extending longitudinally beneath the rollers and provided with an apex 91 directly beneath the bight of the rollers. At each end of the rollers there may be secured to the sheet 90 a plate member 92, at one side of the median line, and a corresponding member 93 at the opposite side of the median line. The two members 92 and 93 at one end of the guide are joined at substantially the apex 91 by means of a screw 94. Each of the members 92 and 93 is provided with an elongated slot 95 cooperating with a rod 96 provided at either side of the wringer. 60 65 70 75 On one of the rods 96 there is pivotally mounted

an arm 97 having a nose or projection 98 adapted to cooperate with a star wheel 99 secured to the shaft of one of the rollers. An elongated slot 100 in the arm 97 cooperates with a stud 101 carried by the member 92. A spring 102 connected between studs carried by the members 92 and 93 serves to normally draw the parts into the position shown in Fig. 13 with the apex 91 of the guide well up in the space between the rollers. It will be apparent that as the roller 10 carrying the star wheel 99 is rotated, the arm 97 will be rocked downwardly a number of times during each revolution. This will cause the apex 91 of the guide to be reciprocated beneath the bight of the rollers with the result that any 15 clothes fed along the surface of the guide will be fed into the bight of the rollers. A positive feeding action is thus established and the tendency of slippage between the rollers and the clothes is substantially eliminated. It will be 20 apparent that the mechanism just described, including the star wheel 99, arm 97, etc. may be duplicated at the two ends of the rollers to insure a uniform action.

Referring now to Figs. 15 and 16, a slightly 25 modified construction for the same purpose, is shown. This may consist of a pair of clothes guides 103 and 104 pivotally carried by rods 105 and 106 extending longitudinally of the rollers at opposite sides of the wringer and extending 30 toward the median line between the rollers. A rod 107 directly in the plane of the median line, may be supported between the guides by arms 108. This rod may suitably carry a bar 109 which extends vertically into the space between 35 the rollers. A series of springs 110 suitably connected to the guides 103 and 104 and to the rod 107, and at their opposite ends to a suitable portion of the frame, may normally tend to hold the parts in the position shown in Fig. 15 with 40 the guides in contact with the rollers. A projection 111 on each of the arms 108 cooperating with a star wheel 112 secured to the spindle of one of the rollers may serve to vibrate or reciprocate the bar 109 a number of times upon each 45 revolution of the rollers. This reciprocation of the bar 109 will positively feed the clothes into the bight of the rollers just as the form of mechanism illustrated in Fig. 13. As will be clear the springs 110 will permit the guides 103 and 50 104 to be yieldingly depressed so as to allow the passage of the clothes.

A still further modification of the lower clothes guides is shown in Figs. 17 and 18. In lieu of providing the reciprocating constructions just explained, the clothes guide 113, which may be generally similar to the guide 80 of Fig. 4, may be provided at spaced intervals with small rollers 114. These may suitably be carried by rods supported by ears 115 bent downwardly from the 60 surface of the guide. These small rollers will grip the clothes as they are fed onto the the guide and will force them to cling to the surface of the cooperating wringing roller. If desired the feed rollers 114 might be added to a vibrating or reciprocating form of guide, such as shown in Fig. 13.

Referring now to Figs. 19 to 25, inclusive, there is shown a modified construction which operates in general in substantially the same way as the 70 construction shown in Figs. 1 to 12, inclusive. There is provided a main frame 116 suitably enclosed. A vertically disposed shaft 117 is adapted to be connected in the usual way to the vertical drive shaft of any conventional form of washing 75

machine. This shaft carries at its upper end a pinion 118 meshing with a gear 119 pinned or otherwise secured to a shaft 120. A clutch element 121 is slidably mounted on the shaft 120 but is splined thereto so as to rotate with the shaft. Projections 122 carried by the element 121 are adapted to be engaged in grooves or notches in the hub of a gear 123. When the projections are so engaged the gear 123 will be driven by the motor or other operating device associated with the washing machine. A spring 124 surrounding the shaft 120 serves to urge the clutch element 121 into effective position. When the gear 123 is rotated it serves to also rotate a gear 125 with which it meshes. This gear in turn meshes with a gear 126. The gear 125 is secured to a sleeve 127 which carries one of the rollers 128. Similarly the gear 126 is secured to a sleeve which carries the other wringer roller 129 of the pair. Whenever the clutch element 121 is effective, while the machine is in operation the two rollers will be rotated in the direction of the arrows in Fig. 22.

Suitable means are provided for creating a desired pressure between the rollers. For this purpose the modified construction employs a series of coil springs 130, two of which are associated with each end of the roller 129. The two springs at each end of the wringer bear against upwardly turned feet formed on a yoke member 131 secured in any suitable way to a shaft 132, which may conveniently pass through the supporting sleeve for the roller 129. The outer ends of the springs 130 cooperate with washers which are held by nuts 133 on the ends of rods 134 passing through the springs. These rods may suitably be provided with bolt heads adapted to cooperate with a yoke member 135 of channel form. Within the channel of this yoke member there is provided an eccentric 136 which is of a diameter equal to the distance between the sides of the channel and is secured to a shaft 137 which conveniently passes through the sleeve 127. It will be understood that the spring construction thus far explained is duplicated at the two ends of the wringer rollers. By the provision of eccentrics 136 adjacent the two ends of the shaft 137, the springs 130 at the two ends of the wringer may be subjected to tension and relieved from tension in unison. Variation in the force supplied by the springs to the rollers may be effected through proper adjustment of the nuts 133.

Means which will now be explained are provided for rotating the eccentrics 136 through a half revolution whenever desired to either establish or relieve the pressure between the rollers. For this purpose there is provided a control knob or button 138 carried at the upper end of a push rod 139. This is normally held in elevated position, as shown in Fig. 22, by a spring surrounding the rod. At its lower end the rod is adapted to engage a shoulder formed on an extension 140 of a face cam member 141. This member is loosely mounted upon the hub of gear 125. A projection 142, best shown in Fig. 21, protruding from the side of the member is normally adapted to cooperate with a projection 143 carried by one face of a combined clutch and clutch shifting member 144. Now, as the knob 138 is depressed, and the member 141 is rocked clockwise (Fig. 22), the projection 142 will be carried clear of the projection 143 and the latter will be permitted to enter a recess or notch 145 formed in the end of the sleeve 127. A spring 146 serves to shift the clutch member 144, when permitted, to engage the projections 143 with the notch 145. The member

144 has a splined connection with the shaft 137 and therefore when rotated by the sleeve 127 will serve to drive the shaft 137. However, rotation of the parts will continue only through a half revolution since the projections 143, 5 after slightly less than a half revolution, will engage the face cam 147 carried by the member 141 and the projection 143 will thus be forced out of the recess 142. The member 141 may be restored to its normal position, shown in Fig. 22, following 10 depression of the knob 138, in any suitable way. A spring might be provided for this purpose, although it is considered preferable to simply rely upon the friction between the sleeve 127 and the member 141 to restore the latter upon release of 15 the knob 138. Any appropriate means may be provided for positively arresting the rotation of the clutch member 144 as it is disengaged from the sleeve 127. For this purpose projections 148 may be provided at diametrically opposite points 20 on one face of the member 144, preferably in line with the projections 143. These projections 148 may cooperate with a pivoted latch 149 which is adapted to swing upwardly from the position shown in Fig. 24 as one of the projections passes 25 beneath it. It will be understood that the projections 148 are only in the path of the arm 149 when the clutch member is disengaged from the sleeve 127. When the clutch is engaged the projections 148 will be shifted out of the plane of 30 the arm 149 and hence this arm will not interfere with the driving of the clutch element. It will be apparent, therefore, that upon each operation of the knob 138, the clutch element 144 and the shaft 137 and eccentrics 136 will be rotated 35 through a half revolution. This will serve to either apply or relieve the tension on the springs and the pressure between the rollers in the manner explained.

Provision is also made for disconnecting the 40 roller drive. For this purpose the clutch element 121 is simply shifted to the left (Fig. 19) to disengage the projections 122 from the gear 123. This is accomplished by the provision of a segmental portion on the element 144 which extends 45 down into the path of a flange or disc 152 extending radially from the element 121. In the rotation of the element 144 from its position shown in Fig. 22 to its position shown in Fig. 24, a cam surface 151 on the segmental portion will 50 engage the right side of the disc 152 (Fig. 23) and serve to shift the latter slightly to the left. As the entire element 144 is now shifted to the left by the cam action of the surfaces 151 during the continued rotation of the element the clutch 55 121 will be shifted still further to the left so that it will be completely disconnected from the gear 123. The rotation of the rollers will thus be arrested simultaneously with the release of pressure between them. Upon the subsequent depression of the knob 138, the element 144 will shift to the right (Fig. 23), as previously explained, and will simultaneously permit the element 121 to shift to the right. Therefore, the gear 123 will be coupled to the shaft 120 and simultaneously the shaft 137 will be coupled to the sleeve 127. This will restore the driving connection to the rollers and at the same time permit a half revolution of the shaft 137 to restore the tension between the rollers. When the element 144 is now disengaged from the sleeve 127 at the end of a half revolution the segmental portion will be entirely above the disk 152 and hence the latter will not be shifted to disengage the roller drive. 60 65 70 75

Any of the forms of clothes guides described in connection with the first form of the invention may be employed in connection with the modified construction. A suitable guide is shown 5 in Figure 25 and designated generally by the reference character 153. Beneath this guide, which is appropriately perforated at points below the rollers to permit the drainage of water, there is mounted a tiltable drain member 154. This is 10 pivotally supported by the wringer frame by means of pivot pins 155. A pair of links 156 may be connected to the tiltable drain at opposite sides of the pivot by hooking around suitable studs 157 carried by the drain. The upper ends 15 of these links may be pivotally connected to a rockable plate 158 which is pivoted to the main frame at 159. A handle 160 extending through the wringer casing and rigidly connected to the rockable plate may serve to swing the latter about 20 its pivot until the handle 160 engages either end of an elongated slot 161 in the cover. A spring 162 may be suitably connected to retain the rockable plate in either position. It will be apparent that the direction of inclination of the tiltable 25 drain 154 may be determined at will by operation of the handle 160. In this way the water drained from the clothes fed between the rolls of the wringer may be directed as desired.

While several illustrative forms of the invention 30 have been disclosed in considerable detail, it will be understood that one or more of the features of the invention may be embodied in wringer structures involving considerable variation from the illustrative disclosures.

35 What I claim is:

1. A wringer which comprises a pair of rolls having their axes in substantially the same horizontal plane, means for guiding clothes to the bight between said rolls from either side, said 40 means extending substantially horizontally beneath said rolls, and means for driving said rolls.

2. A wringer which comprises a pair of rolls, means for guiding clothes to the bight between said rolls from either side, power means for driving 45 said rolls, and means under common manual control deriving power from said power means for bringing the rolls together and for separating them.

3. A wringer which comprises a pair of rolls, 50 means for guiding clothes to the bight between said rolls from either side, power means for driving said rolls, a single manual means for controlling the driving connection between said power means and said rolls to both start and stop 55 the latter, and means controlled by said manual means for bringing the rolls together.

4. A wringer which comprises a pair of rolls, means for guiding clothes to the bight between 60 said rolls from either side, power means for driving said rolls, manual means for controlling the driving connection between said power means and said rolls to start and stop the latter, and means including an eccentric and a strap co-operating therewith controlled by said manual 65 means for yieldingly pressing said rolls together.

5. A wringer which comprises a pair of rolls having their axes in substantially the same horizontal plane, means extending substantially horizontally beneath said rolls for guiding clothes to 70 the bight between said rolls, and means for vibrating said guiding means to feed the clothes between said rolls.

6. A wringer which comprises a pair of rolls having their axes in substantially the same horizontal plane, means extending substantially hori- 75

zontally beneath said rolls for guiding clothes to the bight between said rolls, power means for driving said rolls, and means operated upon driving the rolls for feeding clothes between the rolls. 5

7. A wringer which comprises a pair of rolls having their axes in substantially the same horizontal plane, pivoted, yielding means extending beneath the rolls and urged into engagement therewith for guiding clothes to the bight between said rolls, power means for driving said 10 rolls and means including an element rotatable with one of the rolls for feeding clothes between the rolls.

8. A wringer comprising a frame, a plurality of rollers in said frame having their axes in substantially the same horizontal plane, means extending horizontally beneath said rollers and urged yieldingly toward said rollers for guiding clothes to the bight between said rollers from either side, stationary bearings on said frame for supporting one of said rollers, shiftable bearings 15 slideable on said frame for supporting the other of said rollers and yielding means for shifting said shiftable bearings to bring the rollers into contact. 20

9. A wringer comprising a frame, a plurality of rollers in said frame, stationary bearings on said frame for supporting one of said rollers, shiftable bearings for supporting the other of said rollers, yielding means for shifting said 30 shiftable bearings to bring the rollers into contact and maintaining a pressure between them, power means for rotating said rollers, and connections from said power means for operating said yielding means. 35

10. A wringer comprising a pair of rollers, a power driven shaft, driving connections including a clutch between said shaft and said rollers, said clutch having one element carried by said shaft and means including a manually controlled 40 second clutch carried by said shaft for operating said first mentioned clutch by power from said shaft, said second clutch being automatically disabled after a half revolution.

11. A wringer comprising a pair of rollers, a power driven shaft, driving connections including a clutch between said shaft and said rollers, means including a manually controlled second clutch for operating said first mentioned clutch by power from said shaft, said clutches each 50 having an element carried by said shaft for rotation therewith, said second clutch being automatically disabled after a half revolution, and means operated by said last mentioned means for applying a yielding pressure between said 55 rollers.

12. A wringer comprising a pair of rollers, a power driven shaft, connections including a clutch for driving said rollers by power from said shaft, an eccentric carried by said shaft 60 and adapted to be connected therewith for shifting said clutch, and manually operable means for controlling the operation of said eccentric.

13. A wringer comprising a pair of rollers, a power driven shaft, connections including a clutch for driving said rollers by power from said shaft, an eccentric adapted to be connected with said shaft for shifting said clutch means operated by said eccentric for bringing said rollers together under a yielding pressure, and manually operable means for controlling the operation of said eccentric. 70

14. A wringer comprising a pair of rollers, a power driven shaft, a pair of clutches, one of said clutches being adapted to transmit power 75

from said shaft to drive said rollers and the other of said clutches, and means operated under the control of said other clutch for shifting said first mentioned clutch.

5 15. A wringer comprising a pair of rollers, a power driven shaft, a pair of clutches, one of said clutches being adapted to transmit power from said shaft to drive said rollers and the other of said clutches, and means operated under the 10 control of said other clutch for shifting said first mentioned clutch, and applying a yielding pressure between the rollers.

15 16. A wringer comprising a pair of rollers having their axes in substantially the same horizontal plane, spring means for yieldingly forcing said rollers together, and power means for operating said spring means to bring the rollers together and for applying and relieving the tension on said spring means.

20 17. A wringer comprising a pair of rollers having their axes in substantially the same horizontal plane, spring means for yieldingly forcing said rollers together, power means for driving said rollers and adapted to apply and relieve the 25 tension on said spring means, and a single manual means for simultaneously controlling the driving of said rollers and the tensioning or relief of tension of said spring means by said power means.

30 18. A wringer comprising a pair of rollers having their axes in substantially the same horizontal plane, spring means for yieldingly forcing said rollers together, and power means for applying and relieving the tension on said spring means, said power means including an eccentric arranged to act upon said spring means and draw one of the rollers toward the other.

40 19. A wringer comprising a pair of rollers having their axes in substantially the same horizontal plane, spring means for yieldingly forcing said rollers together, power means for driving said rollers, and common manually controlled means including an eccentric adapted to be operated by said power means for applying and 45 relieving the tension on said spring means, said manually controlled means also controlling the driving connection between said power means and said rollers.

50 20. A wringer comprising a pair of rollers having their axes in substantially the same horizontal plane, spring means for yieldingly forcing said rollers together, and a clothes guide extending substantially horizontally beneath said rollers spring urged into contact therewith.

55 21. A wringer comprising a pair of rollers having their axes in substantially the same horizontal plane, spring means for yieldingly forcing said rollers together, means for rotating the rollers, clothes guiding and feeding means beneath said rollers spring urged toward the rollers, and means for vibrating said guiding and feeding means in synchronism with the rotation of the rollers.

60 22. In a wringer, the combination of a frame; wringer rolls mounted in the frame with an upwardly extending bite; a clothes intake guide directing the clothes into the bite, said guide extending under both rolls and adapted to receive clothes from either side; and means for exerting upwardly yielding pressure to the guide.

65 23. In a wringer, a frame, a pair of pressure rolls mounted in the frame, means carried by the frame to grip and guide material fed to the wringer from either of two substantially opposite directions relative to the frame into the

bite of the pressure rolls, means to rotate said pressure rolls wherein said pressure rolls coact to squeeze the material fed to the guiding means from either of said feeding directions, without reversing the direction of rotation of said pressure rolls.

70 24. In a wringer, a frame, a pair of pressure rolls mounted in the frame in a substantially horizontal plane, means to rotate the rolls, means carried by the frame and arranged to grip materials fed from either of two opposite vertical faces of the frame and guide such materials into the bite of the pressure rolls, said pressure rolls being adapted to coact to squeeze the materials fed from either face of the wringer without reversing the direction of rotation of said pressure rolls.

75 25. The combination of a roll wringing mechanism for a washing machine, means for driving the rolls of said mechanism, a clutch in the driving mechanism, power means for operating the clutch to control the movement of the wringer rolls, and a manually operated member for controlling the power operated clutch control means, said member being readily accessible to the operator when the latter is operating the wringer, and being responsive to a comparatively slight pressure by the operator.

20 26. The combination of a roll wringing mechanism for a washing machine having a plurality 30 of wringer rolls extending horizontally from a vertical axis of support, means aligned with said axis of support, for driving the wringer rolls, a clutch in the connections between said means and said rolls, power means for operating the 35 clutch to control the movement of the wringer rolls, and a manually operated member for controlling the power operated means, said member being readily accessible to the operator when the latter is operating the wringer, and said 40 member being responsive to a relatively small pressure by the operator.

25 27. The combination of a roll wringing mechanism for a washing machine, said mechanism including a gear housing having a vertical axis 45 and adapted to be mounted on the washing machine, means including a shaft aligned with said vertical axis for driving the wringer rolls, a clutch in the driving means, power means for operating the clutch to control the movement of the 50 wringer rolls, and a manually operated member mounted on the wringer mechanism for controlling the power operated means, said member being so mounted on the wringer mechanism as to be readily accessible to the operator 55 when the latter is operating the wringer, and said member being responsive to a relatively small pressure by the operator.

30 28. The combination of a roll wringing mechanism for a washing machine, a support and 60 driving means for the wringing mechanism mounted as a unitary structure with the wringing mechanism, a vertically disposed shaft in said supporting means adapted to be connected with a shaft at the side of the washing machine, 65 a clutch in the driving means, power means for operating the clutch to control the movement of the wringer rolls, and a manually operated member for controlling the power operated means, said member being readily accessible to 70 the operator when the latter is in wringer operating position, and responsive to a relatively slight pressure by the operator.

35 29. In a wringer having cooperating rollers, a driving member, a driven member connected to 75

- at least one of the rollers to rotate the same, a clutch between said members to connect and disconnect the same, power receiving means for operating the clutch, said power receiving means being adapted to be driven by said driving member, means for creating pressure between said rollers, means operable at will for controlling the release of pressure between said rollers, and means controlled by said last mentioned means for connecting said power receiving means with said driven member to operate said clutch to disconnect said members whenever the pressure between said rollers is released.
30. In a wringer having cooperating rollers, a driving member, connections including a clutch between said driving member and rollers for rotating the latter, means adapted to be operated by said driving member for disengaging said clutch, means for creating pressure between said rollers, means operable at will for controlling the

release of pressure between said rollers, and means actuated by said last mentioned means for causing the operation of said clutch disengaging means by said driving member as the pressure between said rollers is released. 5

31. In a wringer having cooperating rollers, an operating shaft, connections including a clutch between said shaft and rollers for driving the latter, a half-revolution clutch, means adapted to be driven by said shaft through said half revolution clutch for disengaging said first mentioned clutch, means for creating pressure between said rollers, means operable at will for controlling the release of pressure between said rollers, and means actuated by said last mentioned means for causing the operation of said half-revolution clutch to disengage said first mentioned clutch as the pressure between said rollers is released. 10 15

THOMAS W. BEHAN. 20
